 a corporation of Maryland

Application April 19, 1939, Serial No. 268,686

10 Claims. (Cl. 123—122)

This invention relates to internal combustion engines and more particularly to the manifolds of engines employing a hydrocarbon fuel.

An object of the invention is to improve the distribution of fuel to the cylinders of an internal combustion engine.

Further objects will appear hereinafter as the description proceeds and will be pointed out more fully in connection with the appended claims.

In the drawing of which there is one sheet and which is to be taken as illustrative rather than as than limiting the invention:

Figure 1 is a partial plan view of an internal combustion engine containing the invention, certain parts being broken away in order more clearly to illustrate the construction;

Figure 2 is a vertical transverse sectional view taken substantially upon a plane as indicated by the line 2—2 of Figure 1 looking in the direction of the arrows; and,

Figure 3 is an end elevational view partially in section upon a plane as indicated by the line 3—3 of Figure 1 and looking in the direction of the arrows.

Referring more specifically to the drawing in which similar reference characters are employed to designate similar parts, the invention is shown as applied to an internal combustion engine of eight cylinders of the overhead valve type. The engine which is designated generally at 10 comprises a motor block 12 which may be of cast iron and provided with the usual cooling water passageways 14 and finished cylinders 16 within which are received pistons 18 connected by means of wrist pins 20 and connecting rods 22 to a crank shaft (not shown). Suitable piston rings 22 are employed for effectively sealing the piston to the cylinder walls. The block is also provided with a valve lifter passageway 24 within which valve lifters 26 may be actuated by a cam shaft (not shown), the upper ends of the valve lifters 26 being provided with head members 28 which are adapted to bear against adjustable stops 30 carried by rocker arms 32 pivoted upon the rock shaft 34 and having depending arms 36 which are adapted to contact the upper ends 38 of valves 40 to depress the same and lower them away from their seats 42. A washer 44 engaging a groove (not shown) in the upper end of the valve stem provides a seat against which the upper end of a valve spring 46 rests, the lower end of the spring resting against the upper surface of the cylinder head 48, which also supports the rock shaft 34 from suitable lugs 50. The

valve stem 38 passes through a guide 52 in the cylinder head 48.

It will be understood that the construction above described is the same for both intake and exhaust valves, it being only necessary to employ slightly different materials in the heads of the valves 40 and to employ different timing for intake and exhaust valves.

The head 48 is also provided with a laterally projecting portion 54 which contains the intake and exhaust manifold passages. The intake manifold passages comprise two longitudinally extending channels 56 and 58 which are formed in the upper surface of the cylinder head extension 54, the channel 56 being of less extent than the channel 58 and positioned approximately midway of the length of the channel 58. The forward and rear portions of the channel 56 are connected to transversely extending passageways or ports 60 for distributing a fuel and air mixture to the intake valves of cylinders number 3, 4, 5, and 6, such lateral passages 60 lying beneath the surface of the head 48 and extending downwardly at an angle to the valve area, as illustrated more clearly in Figure 3. At its central portion the channel 56 is enlarged as at 62 for a purpose to be hereinafter explained.

The manifold channel 58 extends longitudinally of the cylinder head 48 and has its end portions extending diagonally inwardly as at 59 toward the principal axis of the motor for the purpose of saving material. At the ends of the channel 58 passageway 64 extends downwardly and inwardly to the region of the intake valves 40 for cylinders 1, 2, 7, and 8. The central portion of the channel 58 is also provided with an enlarged portion 66 similar to the enlarged portion at 62 of the channel 56.

At this central point and above the channels 56 and 58 there is secured a carburetor 68 provided with a plurality of jets 70 which are divided by a central partition 72 for the purpose of feeding air and fuel mixture separately into the channels 56 and 58. Transverse shaft 74 extending through the body of the carburetor 68 has throttle valves 76 rigidly attached thereto for the purpose of regulating the quantity of fuel and air mixture which is to be fed to the channels 56 and 58 and through them to the cylinders. A second transverse rock shaft 78 extends through the body of the carburetor 68 above the jets 70 and is provided with a butterfly valve 80 for the purpose of providing a choke. It will be understood that suitable connections to the rock

shafts 74 and 78 are provided for permitting their manipulation by the operator.

A cover plate 82 is secured to the top of the head extension 54 over the manifold channels 56 and 58 for the purpose of closing the same, and it is to this cover plate that the carburetor 68 is secured as by means of bolts 84.

Adjacent the exhaust valves 40 (see Figure 2) ports 86 extend laterally to a side surface of the extension 54 as will appear more fully from Figures 1 and 2. The lateral surface 88 of the head to which these ports 86 extend is provided with a partially cylindrical surface 90 against which a tubular exhaust gas collecting conduit 92 may be secured as by means of clamps 94 which are drawn toward the cylindrical surface 90 by means of screws 96. It will be understood that the clamps 94 have a partially cylindrical surface in engagement with the conduit 92 so as to exert a pressure against the conduit 92 sufficient to cause its surface to conform to the finished surface 90 upon the cylinder head without causing distortion or deformation of the tube 92 itself. It will also be understood that the tube 92 is provided with apertures 98 adjacent each port 86 in order that the exhaust gases may readily pass into the tube 92. One end of the tube 92 is provided with a cap 100 which may be secured thereto as by welding for the purpose of closing off such end of the tube. The opposite end of the tube 92 extends to the usual muffler (not shown) through which the exhaust gases are passed prior to exhausting to the atmosphere.

It will be recognized that the enlarged portion 62 and 66 within the channels 56 and 58 provide a storage reservoir within which small quantities of fuel and air mixture may be retained against an emergency. These enlarged portions also serve to permit turbulence of the fuel and air mixture as it issues from the carburetor into the channels 56 and 58 while the passages 56 and 58 are narrowed away from the central portion in order to provide a smooth flow of fuel therein and to reduce such turbulence. The cylinder head is provided with water passageways 102 which surround the valves 40 and communicate with the passageways 14 in the cylinder block for the purpose of conducting heat from the cylinder and from around the valve and head surfaces in order to conduct the heat thereof to a radiator for dissipation of the same in the usual manner. It will also be noted that the passageways 102 and particularly that passageway indicated at 102' in Figure 3 serve to conduct the cooling liquid around the manifold channels 56 and 58 for the purpose of raising the temperature of the entering fuel and air mixture to the operating temperature of the engine thus providing maximum operating efficiency for the engine.

The valve rocker mechanism may be covered by means of a cap 104 which extends thereover and is seated against a gasket 106 supported upon the upper surface of the head 48. Cap screws 108 may be employed to secure the cover in place.

The firing order of the motor illustrated in the drawing will be 1, 6, 2, 5, 8, 3, 7, 4, thus requiring the cylinders to draw fuel alternately from the channels 56 and 58 and imposing no load upon one channel whereby it would be required to supply two successive charges of fuel and air mixture to two different cylinders in the bank fed by its channel. Accordingly, the impulses within each of the channels 56 and 58 will com-

prise two successive impulses in the direction of each end which are spaced apart by impulses in the opposite channel; that is, cylinders Nos. 1 and 2 will draw charges of fuel and air mixture from the channel 58 one after the other but spaced apart by cylinder No. 6 drawing a mixture of fuel and air from the channel 56. The same situation prevails with respect to all of the cylinders as it will be noted from the firing order given above that the two intake valves which lie next to one another upon the ports 60 and 64 follow this same pattern of charge drawing. On the other hand, when the direction of flow within the manifold channels 56 and 58 is reversed as between intake of cylinders No. 2 and No. 8, fuel feeding to cylinder number 5 is interposed and provides an opportunity for the mixture flowing within the channel 58 to reach a stage of equilibrium in order that it may readily reverse its flow.

It will thus be seen that a manifold has been provided which will function in an efficient manner to distribute fuel to the cylinders, and that this manifold will be heated by the cooling liquid flow through the motor and cylinder head to raise the temperature of the fuel and air mixture to that of the motor block whereby more efficient combustion will be obtained.

Although the invention has been described in considerable detail, this description is not to be taken as limiting but merely as illustrating the best known method of practicing the invention. All equivalents falling within the scope of the attached claims are reserved.

I claim:

1. In an internal combustion engine, a cylinder head, a valve mechanism within the cylinder head and operative to admit quantities of fuel and air mixture to the motor, a manifold for distributing fuel and air mixture to the intake valves including a pair of longitudinally extending, spaced channels formed in and open on the upper surface of the head, each of said channels having its ends connected to a plurality of cylinders for the purpose of distributing fuel thereto.

2. A manifold for distributing a fuel and air mixture to an internal combustion engine comprising channels formed in a portion of the engine, a removable cover plate for said channels, branches connecting the ends of said channels to intake valves, and cooling liquid passages extending about and in contact with said channels and said branches to raise the temperature of the same and of the mixture flowing therealong to the temperature of the motor.

3. An internal combustion engine comprising a cylinder block, a cylinder head secured to said cylinder block and containing valve mechanism for admitting charges of fuel and air to the cylinders and exhausting spent gases from the cylinders, intake manifold channels arranged in the upper surface of said cylinder head and having their ends terminating in branches leading to the intake valves of said engine and horizontally extending exhaust channels extending to a lateral surface of said cylinder block, said branches extending inwardly and downwardly to the vicinity of said intake valves, and said exhaust ports extending laterally below said intake channels.

4. In an internal combustion engine of the overhead valve type, a motor block, cylinders formed in said motor block, a cylinder head for said motor block, an intake manifold formed as an open channel in the upper surface of said

cylinder head and extending longitudinally of said head, branch passages in said cylinder head extending laterally and downwardly from said manifold and communicating with said cylinders, means for closing said manifold, and a carburetor located above said manifold and adapted to discharge downwardly into said manifold.

5. In an internal combustion engine motor parts including a motor block and a cylinder head, cylinders formed in said motor block, an intake manifold formed as an open channel directly in an upper surface of one of said motor parts and extending longitudinally thereof, branch passages in said motor part extending laterally from said manifold and communicating with said cylinders, means for closing said channel, and a carburetor located above said manifold and discharging downwardly thereinto, said carburetor being supported by said closing means.

6. In an internal combustion engine motor parts including a motor block and a cylinder head, cylinders formed in said motor block, an intake manifold formed directly in an upper surface of one of said motor parts and extending longitudinally thereof, branch passages in said motor part extending laterally from said manifold and communicating with said cylinders, a carburetor located above said manifold and discharging downwardly thereinto, and exhaust passages in said motor part extending laterally beneath said manifold and connecting said cylinders with an exhaust manifold secured to a side surface of said motor part.

7. In an internal combustion engine of the overhead valve type, a motor block, cylinders formed in said motor block, a cylinder head for said motor block, an intake manifold formed in the upper surface of said cylinder head and extending longitudinally of said head, branch passages in said cylinder head extending laterally and downwardly from said manifold and communicating with said cylinders, and exhaust passages formed in said head and extending laterally beneath said manifold and connecting said cylinders with an exhaust manifold secured to a side surface of said head.

8. In an internal combustion engine of the overhead valve type, a motor block, cylinders formed in said motor block, a cylinder head for said motor block, an intake manifold formed in the upper surface of said cylinder head and extending longitudinally thereof, branch passages in said cyl-

inder head extending laterally and downwardly from said manifold and communicating with said cylinders, a carburetor located above and discharging downwardly into said intake manifold, and exhaust passages formed in said head and extending laterally beneath said intake manifold and connecting said cylinders with an exhaust manifold secured to a side surface of said cylinder head, the flow of fuel and air mixture from said carburetor to said cylinders being always downward or horizontal and never upward to distribute fuel and air mixture to said cylinders in the most efficient manner.

9. In an internal combustion engine, motor parts including a motor block and a cylinder head, cylinders formed in said motor block, an intake manifold formed directly in an upper surface of one of said motor parts and extending longitudinally thereof, branch passages formed in said motor part and extending laterally from said manifold and communicating with said cylinders, and exhaust passages formed in said motor part and extending laterally beneath said intake manifold and connecting said cylinders with an exhaust manifold secured to a side surface of said motor part, said exhaust passages and said intake manifold being provided at least in part with common walls whereby heat from the exhaust gases is transmitted directly to the fuel and air mixture in the intake manifold.

10. In an internal combustion engine, motor parts including a motor block and a cylinder head, cylinders formed in said motor block, an intake manifold formed directly in an upper surface of one of said motor parts and extending longitudinally thereof, branch passages formed in said motor part and extending laterally from said manifold and communicating with said cylinders, and exhaust passages formed in said motor part and extending laterally beneath said intake manifold and connecting said cylinders with an exhaust manifold secured to a side surface of said motor part, said exhaust passages and said intake manifold being provided at least in part with common walls whereby heat from the exhaust gases is transmitted directly to the fuel and air mixture in the intake manifold, and another portion of the walls of said exhaust passages being surrounded by cooling fluid passageways which also extend into heat transfer relation with said intake manifold.
